United States Patent Office.

BENJAMIN J. HARRISON AND JAMES CONDIE, OF NEW YORK, N. Y.

Design No. 2,685, dated June 25, 1867.

DESIGN FOR A FOLDING CHAIR.

The Schedule referred to in these Letters Patent and making part of the same.

TO ALL WHOM IT MAY CONCERN:

Be it known that we, BENJAMIN J. HARRISON and JAMES CONDIE, both of the city, county, and State of New York, have invented a new and useful Design for Folding Chairs; and we do hereby declare that the following is a full, clear, and exact description of the same, reference being had to the accompanying drawings, making a portion of this specification, in which—

Figure 1 is a front view, representing a folding chair made according to our invention.

Figure 2 is a side view of the same.

Figure 3 is a transverse section of the arm of the chair, taken in the line $z z$ of fig. 2.

Similar letters of reference indicate corresponding parts in all the figures.

The uprights a of the back of the chair are round, and slightly tapering at their upper portions, and below the said portion each upright is made rectangular for a short distance, as shown at a^1 , and below this has its profile formed, first, of re-entrant curves, as at a^* , and then toward its extremity with salient curves a^2 . The main or nearly horizontal portions b of the arms B of the chair are slightly curved, and their forward extremities are turned or curved downward in front of the posts c , as shown in fig. 2; the said arms being furthermore rounded off at their upper and lower sides, in the manner indicated in the cross-section, fig. 3. The upper portions c' of the posts c are cylindrical, while the remaining parts thereof correspond in shape to the lower portions $a^* a^2$ of the uprights a . The two side rails C of the bottom are made with flat lateral and under surfaces, but with the edges of the upper sides bevelled at intervals, as shown respectively at d and d' , wholly flat portions d^* of such upper sides being left immediately under the posts c and uprights a . The side bars D of the legs are made with flat sides, except that the lateral edges of the lower sides are rounded off, as shown at e' . The crossed legs E are each formed with a cylindrical upper portion, f , below which the profile of the leg is described by salient curves f^* , alternate with re-entrant curves f' . The central and lower enlarged portions of the forward pair of legs are made flat in front, as shown at g' in fig. 1.

What we claim as our invention, and desire to secure by Letters Patent, is—

The design for a folding chair, substantially as herein set forth.

BENJ. J. HARRISON,
JAMES CONDIE.
